UNITED STATES PATENT OFFICE.

EDWARD S. HALSEY, OF NAHANT, MASSACHUSETTS, ASSIGNOR TO GENERAL ELECTRIC COMPANY, A CORPORATION OF NEW YORK.

MERCURY-METER.

1,003,453.

Specification of Letters Patent. Patented Sept. 19, 1911.

Application filed April 22, 1908. Serial No. 428,631.

To all whom it may concern:

Be it known that I, EDWARD S. HALSEY, a citizen of the United States, residing at Nahant, county of Essex, State of Massachusetts, have invented certain new and useful Improvements in Mercury-Meters, of which the following is a specification.

My invention relates to electric meters, and more particularly to that type of electric meter where the armature revolves in a receptacle containing a conducting fluid such as mercury, and has for its object an improvement in the construction of such meters.

15 In the meter art it is particularly desirable to construct meters as cheaply as possible, since very many are in use, and meters are frequently used where the consumption of electrical energy is so small that it would 20 not pay to install an expensive meter for the measuring of such a consumption.

A feature of my invention then, is the construction of a cheap meter by forming the retaining member, which holds the mercury 25 and surrounds the revolving armature, out of some magnetic substance which may form a pole-piece for the torque-producing magnets, and will be cheap to make and simple and substantial in its construction.

30 Another feature of my invention is to produce a large torque in the meter-armature, and this I accomplish by producing as large a flow of current as possible within the region of the field produced by the poles of 35 the torque-producing magnet.

Another feature of my invention is a construction which will hold the meter-armature as constantly as possible in one position in the surrounding mercury, and I accomplish this by making the meter-armature in a cup-shape, open at the top and rigidly fastened to a shaft which bears upon a lower bearing which is contained in the retaining member, and has its bearing surface in close 40 proximity to the juncture of the armature and the shaft. By this form of construction, the armature will be held more constantly in place than it would be if it were fastened at approximately the center of the 45 shaft, since, in the latter case, owing to the liability of the shaft to bend from its normal position, there is more tendency for a movement of the armature than if the armature is fastened near one end of the shaft.

50 Another feature of my invention is the

use of a cover for the mercury surrounding the armature, which will allow only a small portion of the mercury to come in contact with the surrounding atmosphere, and thus prevent oxidation, which may alter or increase the friction between the mercury and the armature.

For a further understanding of my invention reference may be had to the accompanying drawings, in which—

Figure 1 shows a front view of my meter, with a portion of the cover removed; Fig. 2 is a vertical section of my meter taken from the side; Fig. 3 is a top view of my meter with the registering train removed and portions of the meter shown in section; and Fig. 4 is a detail view on a large scale of a portion of my meter, showing the shipping device.

I have shown a back 1, to which may be attached a cover 2, in any suitable fashion, and a hollow cup-shaped retaining member 3 made of a magnetic material with lugs for attaching it to the back 1, and with other lugs for attaching a cover to it, and also a frame for supporting portions of the meter mechanism. Member 3 may be attached to the back of the meter in any suitable way, such as by means of screws 4.

55 5 is a cover of non-magnetic material fastened so as to go within the cup-shaped portion of member 3, leaving a space between it and the interior of the cup-shaped portion of member 3, which space may be filled with any conducting fluid, but I prefer the use of mercury, and in which space the meter armature revolves. Cover 5 rests upon the top of member 3, and has suitable lugs, so that it may be fastened to member 3 by means of screws 6, or in any other way, and allows 60 only the small surface of mercury in hole 9' made in the cover for the passage of the meter shaft to be exposed to the air.

65 I have shown an armature 7, made in the shape of a cup open at the top, that may be made of any conducting substance, and revolves in the mercury filling the space between members 3 and 5, and has a conducting ring 8 attached to its upper portion for increasing the eddy currents in it.

70 Rigidly attached to the armature is a meter shaft 9 which at its lower extremity rests upon a bearing 10, which may be constructed in any desired manner and attached to the lower portion of member 3 and is in 75

close proximity to the juncture of the armature and the shaft. I have shown a cap 11 surrounding this bearing and screwed onto a suitable projection upon member 3. Shaft 9, by any suitable mechanism such as a worm and gear wheel 12, drives the registering mechanism 14, which may be of any suitable type. The upper end of shaft 9 is supported by a bearing, which is supported 5 by frame 13, which is fastened to suitable lugs 13' formed in member 3. Frame 13 I have also shown as supporting the registering train 14.

Surrounding the meter shaft I have shown 10 a weight 15 which is normally held in position by a distorted spring 16. This weight serves as a counter-balance against the upward thrust of the mercury upon the armature, and also serves as a shipping device for 15 preventing the escape of the mercury when the meter is being transported. I have shown a sleeve 17 inserted in the top of cover 5 and surrounding the shaft and having an internal thread in which may be 20 screwed weight 15 by means of a suitable projection which is formed upon its lower side. I have shown a gasket 18 so that when the weight is screwed down into the sleeve the gasket will make a tight joint. 25 I have also shown a stuffing-box 18' at the top of weight 15.

I have shown permanent magnets 19 and 30, which are made in the form of a U, and have two sides of similar polarity bolted 35 together by means of bolts 21, so as to form a consequent pole. The other ends of these magnets are fastened to lugs 22 and 23 on member 3 by means of screws 24. The consequent poles are fastened to a magnetic 40 member 25, which goes through a suitably formed hole in the top of cover 5, and is in close proximity with a side of the meter armature and a portion of the bottom. This pole-piece is fastened to the consequent poles 45 of the magnets in any way, such as by screws 26, and is fastened to cover 5 by means of screws 27, whereby it tends to support the permanent magnet.

I have shown two conductors 28 and 29, 50 which are brought down through the cover 5 into close proximity with the armature, one conductor 28 extending through member 5, so as to make contact with the fluid surrounding the armature at the bottom of 55 the armature, and the other conductor 29 coming in contact with the fluid surrounding the armature at a point slightly above the side of the armature. These two conductors are arranged so that when current is 60 passed through them, the current will flow through the meter armature in a stream in close operative relation with pole-piece 25 flowing across the bottom and along one side of the pole-piece in a longitudinal direction. Conductors 28 and 29 are attached

65 to binding-posts 30 and 31, and I have shown cables 32 and 33 attached to studs 34 and 35, which may be used in the well-known way for connecting the circuit to be measured to the meter.

The operation of my meter will then be 70 as follows: When current is caused to flow through the meter, it will pass through the portion of the armature between conductors 28 and 29, and will cause a torque to be developed in the armature, as it is affected by the permanent magnet. The armature will then revolve, but will be retarded in the well known fashion by eddy currents generated in it and its attached 75 ring 8.

80 While I have described a certain form and construction in which my invention may be carried out, I do not limit myself to this form or construction, as many forms and constructions that do not depart from the scope of my invention, and which I seek to cover by the appended claims, will be 85 obvious to those skilled in the art.

89 What I claim as new and desire to secure by Letters Patent of the United States, is—

95 1. In a mercury meter, a magnet, a cup-shaped rotatable armature, a magnetic member surrounding the armature and forming one pole of the magnet, and a magnetic member forming the other pole of the magnet extending within the armature in operative relation to a portion only of the side and the bottom of the armature.

100 2. In a mercury meter, a cup-shaped armature, a magnetic member surrounding the armature, and two U-shaped magnets with two of their sides fastened together so as to form a consequent pole extending 105 within the meter armature and their other two sides fastened to the magnetic member surrounding the exterior of the meter armature.

110 3. In a mercury meter, a cup-shaped armature, a magnetic member surrounding the armature and forming a magnetic pole, a second magnetic pole within the armature adjacent to one side only and a portion of the bottom, a current conductor in close relation to a portion of the top of the armature, and a second conductor in close relation to the bottom of the armature adjacent to the second magnetic pole causing the current to flow through the armature along 115 a side and across the end of the second magnetic pole.

120 4. In a mercury meter, a cup-shaped armature, a magnet, a magnetic member surrounding the armature and forming one pole of the magnet whose second pole extends within the armature in close relation to one side and a portion of the bottom, a current conductor in close relation to a portion of the top of the armature, and a 125

second conductor in close relation to the bottom of the armature causing the current to flow through the side of the armature adjacent the interior magnetic pole, and 5 through the bottom adjacent the end of the interior magnetic pole.

5. In a mercury meter, mercury, a magnetic cup-shaped retaining member, a cover therefor, a magnetic member extending therethrough, a rotatable cup-shaped armature revolving in the mercury between the retaining member and the cover, two permanent U-shaped magnets having two of their similar poles fastened to the retaining 10 member and their other two poles fastened to the magnetic member extending through the cover in close relation with one side and a portion of the bottom of the armature, a current conductor in close relation to a 15 portion of the top of the armature, and a second current conductor in close relation to a portion of the bottom of the armature causing the current to flow through a side of the meter armature and a portion of its 20 bottom influenced by the magnets.

6. In a mercury meter, a rotatable cup-shaped armature open at the top, a magnetic retaining member surrounding the sides and bottom of the armature, a non-magnetic cover therefor fitting within the 25 armature, a magnet having as one of its poles the retaining member, and having the other pole extending within the cover in operative relation to the armature.

35 7. In a mercury meter, a rotatable cup-shaped armature open at the top, a shaft rigidly fastened to the armature, a magnetic retaining member forming one pole of a magnet, surrounding the armature and 40 containing a bearing for the shaft in close proximity to its juncture with the armature.

8. In a mercury meter, a rotatable cup-shaped armature open at the top, a shaft

rigidly fastened thereto, a magnetic retaining member surrounding the armature and containing a bearing for the shaft in close proximity to the juncture of the shaft and armature, and a magnet having as one pole 45 the retaining member and having the other pole extending within the armature.

9. In a mercury meter, mercury, a magnetic retaining member surrounding the armature a rotatable armature open at the top revolving in mercury held by the retaining member, a cover for the retaining member extending within the armature and inclosing the mercury so as to only permit 50 of a small surface contact between the mercury and the surrounding air.

10. In a mercury meter, a rotatable cup-shaped armature open at the top, a magnetic cup-shaped retaining member surrounding the same, a shaft rigidly attached to the armature and with its lower end 55 bearing on a bearing contained by the retaining member and in close proximity to the juncture of the shaft and armature, a cover for the retaining member inclosing the armature so as to have a space between the 60 armature, the cover and the retaining member, a magnetic member extending through the cover, mercury filling the space, two U-shaped magnets having two of their similar poles attached to the retaining member and 65 the other poles fastened to the magnetic member and forming a consequent pole extending through the cover in operative relation to the meter-armature and current-conductors causing current to flow through 70 the armature.

In witness whereof, I have hereunto set my hand this tenth day of April, 1908.

EDWARD S. HALSEY.
